UNITED STATES PATENT OFFICE.

FRANK W. McDERMOTT, OF RAWLINS, WYOMING.

GLAZIER'S TOOL.

1,153,092.

Specification of Letters Patent.

Patented Sept. 7, 1915.

Application filed September 4, 1914. Serial No. 860,270.

To all whom it may concern:

Be it known that I, FRANK W. McDERMOTT, a citizen of the United States, residing at Rawlins, in the county of Carbon and 5 State of Wyoming, have invented new and useful Improvements in Glaziers' Tools, of which the following is a specification.

This invention relates to glaziers' tools and more particularly to glass cutters, the 10 object of the invention being to provide simple and efficient devices for cutting glass in circles or rings of any size.

Another object of the invention is to provide a device of the character described in 15 which the bearing will be tight when the device is in operative position, irrespective of the wear thereon.

Further objects of the invention will appear as the following description is read 20 in connection with the accompanying drawing, which forms a part of this application, and in which:—

Figure 1 is a side elevation. Fig. 2 is a 25 top plan view. Fig. 3 is a vertical sectional view taken through the head. Fig. 4 is a similar view taken at right angles to Fig. 3.

Referring more particularly to the drawing, 1 represents a circular disk slightly concaved on its under side, as shown in Fig. 30 3, and provided with a pad of any suitable friction material 2 such as rubber or the like which is adapted to engage the glass and hold the support against movement while the device is in operation. Projecting 35 vertically from the disk is a circular boss 3 having a central recess 4 and a ball race 5 in its upper face which surrounds the recess. Seated within the recess is the grooved projection 6 projecting longitudinally from one 40 end of the bearing head 7 which has a ball race 8 formed in one end and surrounding the projection 6. Balls 9 are arranged in the ball races 5 and 8 and the projection is secured in the recess 4 by means of a set 45 screw 10 which engages the groove therein so as to permit turning of the head upon the boss 3. The upper end of the head 7 is provided with a ball race 11 and a grooved projection 12 corresponding to the projection 6 and adapted to enter a recess 13 formed in the pressure head 14. This pressure head is also provided with a ball race 15 and a set screw 16 for engaging the groove in the projection 12. Balls 17 are

received in the races 11 and 15, as shown 55 in Figs. 3 and 4.

The head 7 is provided with a transverse slot 18 gradually decreasing in height from its outer ends to a point intermediate the width of the head to form knife edged fulcrumed points directly in alinement with the longitudinal center of the bearing head 7, as shown, and adjustably mounted within this slot between the fulcrumed points is a graduated sweep arm 19 having a lateral 65 notched cutter receiving head 20 on its outer end. A cutter of any suitable character is held in the notch by means of a set screw 21 and the sweep arm is held in adjusted position within the bearing head 7 by means of 70 a set screw 22.

It will be noticed in the operation of the device that when pressure is applied to the head 14 to hold the support firmly on the glass that the bearings are also held tight. 75

What is claimed is:—

1. In a glass cutter, a support having a friction pad upon its bottom, a pressure head, a bearing head rotatable within and between said support and pressure head, 80 said bearing head having a transverse slot of gradually decreasing height from its outer ends to a point intermediate the width of said head to form a knife edged fulcrumed point directly in alinement with the longitudinal center of said base and bearing head, a sweep arm fulcrumed upon said edges and longitudinally removable through said slot, and clamping means carried by said bearing head. 85

2. In a glass cutter, a support, a pressure head, a bearing head rotatable in and between said support and pressure head, said bearing head having a transverse slot of gradually decreasing height from its outer 95 ends to a point intermediate the width of said head to form a knife edged fulcrumed point, a sweep arm disposed between said points to permit vertical movement of its ends and means carried by said bearing head 100 for locking said arm against movement.

In testimony whereof I affix my signature in presence of two witnesses.

FRANK W. McDERMOTT.
